UNITED STATES PATENT OFFICE.

CARL T. PENTON, OF DETROIT, MICHIGAN.

DESIGN FOR A TRANSMISSION-CASE FOR A TRACTOR.

58,626.

Specification for Design.

Patented Aug. 2, 1921.

Application filed March 5, 1921. Serial No. 450,102. Term of patent 14 years.

To all whom it may concern:

Be it known that I, CARL T. PENTON, a citizen of the United States, residing at Detroit, in the county of Wayne and State of Michigan, have invented a new, original, and ornamental Design for a Transmission-Case for Tractors, of which the following is a specification, reference being had to the accompanying drawing, forming part thereof.

In the drawings,

Figure 1 is a rear end view in elevation of my design for a transmission case for tractors.

Fig. 2 is a side view in elevation of the design as shown in Fig. 1.

Fig. 3 is a front end view in elevation of the design as shown in Figs. 1 and 2.

I claim—

The ornamental design for a transmission case for a tractor as shown.

CARL T. PENTON.

Signed in the presence of—

M. E. BROESAMLE.
